Primary Examiner — Jennifer Rivard(74) *Attorney, Agent, or Firm* — Panasonic IP Management; Kerry S. Culpepper(57) **CLAIM**

We claim the ornamental design for an electric clipper, as shown and described.

DESCRIPTION

FIG. 1 is a front perspective view of a first electric clipper of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view.

FIG. 9 is a front perspective view of a second electric clipper of the present invention;

FIG. 10 is a rear perspective view thereof;

FIG. 11 is a front view thereof;

FIG. 12 is a rear view thereof;

FIG. 13 is a first side view thereof;

FIG. 14 is a second side view thereof;

FIG. 15 is a top view thereof; and,

FIG. 16 is a bottom view thereof.

The broken lines illustrate a portion of the electric clipper and form no part of the claimed design.
